UNITED STATES PATENT OFFICE.

ALBERT W. HAM, OF LANSINGBURG, NEW YORK.

TROLLEY-TENDER.

SPECIFICATION forming part of Letters Patent No. 691,263, dated January 14, 1902.

Application filed April 8, 1901. Serial No. 54,777. (No model.)

To all whom it may concern:

Be it known that I, ALBERT W. HAM, a citizen of the United States, residing in Lansingburg, in the county of Rensselaer and State 5 of New York, have invented a new and useful Improvement in Trolley-Tenders, of which the following is a specification.

My invention relates to trolley-tenders for reeling in the slack of trolley-cords attached 10 to the trolley-carrying poles of ordinary construction which are used on cars in overhead-wire electric traction systems. The functions to be performed by the trolley-tender are as follows: to reel in slack of the trolley-cord as the trolley is depressed, as when 15 the car goes under bridge, and to pay out the trolley-cord as the trolley rises, as when the car comes from under a bridge, and also in case the trolley jumps from the wire to catch 20 the cord immediately and prevent the trolley-pole from swinging violently to a vertical position. The dangers and inconveniences which result from this accident are too well known to require description.

25 In the drawings hereto annexed I have shown one form in which my invention may be embodied, and therein—

Figure 1 is a front view of my improved trolley-tender; Fig. 2, a vertical transverse 30 section; Fig. 3, a side view, and Fig. 4 a sectional elevation on the line 4 4 of Fig. 2 looking from the back side.

The trolley-tender is secured to a convenient place on the car, preferably to the rear 35 dashboard just above the usual place for the dashboard-lantern. The mode of attachment shown in Fig. 1 is by a blade E, which is secured to the dashboard at e and offset slightly at e⁴, so that by means of a slot in the rear 40 part of the tender-case, presently to be described, the trolley-tender may readily be slipped on and off the blade E. A notch e' in the free end of the blade E serves to retain a hook e², which is attached to the tender-case by a chain e³. This hook keeps the trolley-tender in place on the blade E. The trolley-cord, or a flexible chain or band which may be attached to the trolley-cord, enters 45 the tender-case at the opening c³, Fig. 1, and winds around the spring-actuated reel R, which is mounted inside the case.

The tender-case is constructed as shown in Fig. 2. The shell is composed of a back plate A, flanged at a, and a dished cover C, flanged at c, the cover C fitting over the back- 55 plate flange a, to which it is secured by screws c². The screws c² pass through the flanges a and c into the base-plate B. At the sides of the tender-case the flanges a and c are cut away at a' and c', Fig. 3, so as to provide for 60 the admission of the blade E, Fig. 1. The base-plate B is provided with a broad transverse groove b, which registers with the recesses a' and c', so that when the trolley-tender is assembled there is provided a slot or 65 opening from side to side for the blade E.

Secured to or cast integrally with the base-plate B there is the shoulder b' and stem b², which serve as side and pivot bearings, respectively, for the reel R. On the inside of 70 the cover C there is formed the boss c', which acts as an opposite end bearing for the reel. A washer b³ and screw b⁴ secure the several named parts firmly in place. The reel R is made hollow, so as to contain the actuating-spring S. This spring is coiled inside the reel and is secured at one end to the stem b² and at the other to the inside of the drum r². The side plates r r' form with the drum r² an annular winding-space for the 80 cord T. The spring S is properly set, the cord T wound on the reel R, and the tender-case secured to the dashboard of the car by means of the blade E. As the trolley rises and falls by reason of changes in the elevation of the overhead wire the spring-actuated reel R pays out and winds up slack cord. 85

On the rear plate of the reel R there are fixed a suitable number—say three—of pins or screws r³, which project from the plate r'. On 90 a stud b⁵, secured to the back plate B, there is mounted a freely-movable catch D, which is best shown in Fig. 4. The catch D in the form of construction here shown is a lever provided with a hook d' at one end and a 95 knocker d² at the other. The stud b⁵ acts as a pivot for the catch. The knocker d², which in this embodiment of my invention is part of the catch D, normally projects into the path of the pins r³, which as they rotate with the reel keep hitting the knocker, and thereby 100 agitate the catch D. The connection (in this

construction) between the knocker and the hook or catch serves to communicate the impact of the actuators to the catch. The hook end d' of the catch D is heavier than the knocker end, so that normally the hook d' is out of engagement with the reel, the normal winding and unwinding of the cord T being insufficiently rapid to cause the pins r^3 , which are actuators for the catch D, to throw the hook d' into engaging position; but the instant the trolley-pole is suddenly released, as by the trolley jumping from the wire, the unusually rapid rotation of the reel R in the direction of the arrow, Fig. 4, causes the catch-actuators r^3 to strike the knocker of the catch D vigorously and to throw the hook d' up to the point where the actuating-pin r^3 catches in the hook and brings the reel, cord, and trolley-pole to a standstill. The reel-engaging position of the catch D is shown in dotted lines in Fig. 4. When the car-conductor pulls the trolley-pole down to replace the trolley, the rewinding of slack removes the pin r^3 from the hook d' , which falls to its normal position. Thus the trolley-tender automatically resets itself. In reversing the direction of movement of the car the conductor merely lifts the hook e^2 out of the notch e' , Fig. 1, pulls the trolley off the wire, takes the trolley-tender off the blade E, and then puts the

apparatus on the other dashboard, which is similarly provided with an attaching-blade E.

What I claim, and desire to secure by Letters Patent, is—

1. In a trolley-tender, the combination of a spring-actuated reel, a pivoted catch-lever mounted adjacent to the reel, having a weighted end with a hook thereon, and a light end normally in the path of catch-knockers, the catch-knockers, secured to the reel, whereby, when the reel is rotated at unusual speed the heavy end of the catch-lever is knocked to a position of engagement with a catch-knocker. 35

2. In a trolley-tender, the combination of a spring-actuated reel, a pivoted catch-lever mounted adjacent to the reel with one end provided with a hook and the other normally in the path of catch-knockers, the catch-knockers secured to the reel, and so spaced with relation to the length of the catch-lever 40 that the same knocker which impels the catch into reel-stopping position is intercepted by the hook. 45

Signed by me at Troy, New York, this 5th day of April, 1901.

ALBERT W. HAM.
